UNITED STATES PATENT OFFICE.

FRANK W. MERRILL, OF DEERING, MAINE, ASSIGNOR TO THE E. T. BURROWES COMPANY, OF PORTLAND, MAINE.

REFRIGERATING-RECEPTACLE.

SPECIFICATION forming part of Letters Patent No. 568,579, dated September 29, 1896.

Application filed April 2, 1896. Serial No. 585,958. (No model.)

To all whom it may concern:

Be it known that I, FRANK W. MERRILL, a citizen of the United States, residing at Deering, in the county of Cumberland and State 5 of Maine, have invented certain new and useful Improvements in Refrigerating-Receptacles; and I do hereby declare the following to be a full, clear, and exact description of the invention, such as will enable others skilled 10 in the art to which it appertains to make and use the same.

This invention relates to refrigerator-receptacles, and it is embodied in the construction and arrangement of parts hereinafter 15 described, and definitely pointed out in the claim.

The invention is primarily intended for use in connection with what are known as "ice-cream refrigerators," and it comprises 20 a construction whereby the can or holding-receptacle may be firmly supported and conveniently removed from the box or casing.

In the drawings, wherein like letters of reference designate corresponding parts in the 25 several views, Figure 1 is a perspective view of a can. Fig. 2 is a vertical section of a can and jacket, and Fig. 3 is a detail view of the removing-ring.

In the drawings, A designates a perforated 30 jacket having the centering-ring B at its top. This jacket is adapted to be inserted in any convenient form of refrigerating-receptacle.

C designates the can, which is fashioned to fit within the jacket and has adjacent to its 35 upper edge the divided supporting flange or flanges D D' of a width sufficient to project over the edge of the jacket, which latter thereby serves as a support for the can. The flanges D extend but part way around the can on 40 opposite sides, and the spaces between their adjacent ends form what may be properly

termed "grooves" or "ways," designated at d and located diametrically opposite each other.

E designates the lifting-ring, fitting closely about the can and normally resting with its 45 upper edge against the flanges D D'. On diametrically opposite sides of the ring E are secured the handles H, the same consisting of the vertical sections f, which extend from the ring upward above the plane thereof, and 50 the angle or lifting sections f', which are carried out substantially horizontal to points above and beyond the jacket. The vertical portions of the handles extend through the grooves d to points above the flanges, by which 55 means the flanges are permitted to rest entirely on the jacket without interference by the handles.

By the construction above described it will be seen that the can is evenly supported and 60 can be readily lifted from the jacket.

While a particular form of handle has been shown and described, it is to be understood that the same may be varied or changed in many respects without departing from the 65 nature of the invention.

Having thus described the invention, what is claimed as new, and desired to be secured by Letters Patent, is—

The combination with separated can, having 70 projections thereon, of a lifting-ring surrounding the can and resting against the projections, handles on the ring extending upwardly between and beyond the projections, and a support on which the projections rest, 75 substantially as described.

In testimony whereof I affix my signature in presence of two witnesses.

FRANK W. MERRILL.
